F. E. BEST

LOCK

Filed March 18, 1922

Frank Eller Best,
INVENTOR

UNITED STATES PATENT OFFICE.

FRANK ELLISON BEST, OF SEATTLE, WASHINGTON, ASSIGNOR TO FRANK E. BEST, INC., OF SEATTLE, WASHINGTON, A CORPORATION OF WASHINGTON.

LOCK.

Application filed March 18, 1922. Serial No. 544,918.

To all whom it may concern:

Be it known that I, FRANK ELLISON BEST, a citizen of the United States, residing at Seattle, in the county of King and State 5 of Washington, have invented a new and useful Lock, of which the following is a specification.

This invention relates to improvements in locks, and more particularly to locks of 10 that character described and illustrated in United States Patent No. 1,384,022, issued to me on July 5, 1921.

The principal objects of the present invention are: First, to provide a more simplified, less expensive and more desirable construction, than in the previous lock, yet retaining all its advantages and desirable features; second, to provide a lock construction that may be more easily and more 20 readily disassembled, if such should be desired for the re-setting of combinations; third, to provide a locking gate of a more simplified construction than before used.

In accomplishing these and other objects 25 of the invention, I have provided the improved details of construction, the preferred forms of which are illustrated in the accompanying drawings, wherein—

Figure 1 is a vertical, longitudinal section taken centrally through the lock, with 30 a key in position for operating the primary locking mechanism.

Figure 2 is a transverse, sectional view 35 through the lock, taken on the line 2—2 in Figure 1.

Figure 3 is an inner end view of the lock.

Figure 4 is a horizontal, sectional view 40 taken on the line 4—4 of Figure 2, with the core removed illustrating the manner of 45 and means for securing the lock housing against unauthorized removal.

Figure 5 is a horizontal section on the line 5—5 in Figure 2, particularly illustrating the manner of locking the core to 45 the face plate.

Figure 6 is a detail, perspective view of 50 the locking gate and a portion of the key plug sleeve.

Referring more in detail to the several 55 views of the drawings, wherein like reference numerals designate the same or like parts—

1 designates the lock housing which is of 55 a cylindrical form threaded about its inner end as shown at 2, and provided about

its outer end with a collar 3 that is fixed thereto in any suitable manner and which is adapted, when the housing is inserted within a door or the like designated at 4, to seat against the outer face thereof or against an escutcheon plate 5 which would be secured to the door. When the housing is inserted, its inner end is threaded within an opening in the wall plate 6 of a latch casing within the door, as is shown in 65 Figure 1, and, in order that it may be secured against unauthorized removal, I have provided a bore 7, leading from a point just within the opening through the housing which is provided for the insertion of the 70 core as will be presently disclosed, at an incline to the outer side of the housing and provided with a threaded outer end portion wherein a locking screw 8 is threaded, with its outer end projecting from the housing 75 and seated within a notch 9 in the plate 6, as is shown in Figures 4 and 5, to prevent any possible unthreading, or turning of the housing. It will be apparent that after the 80 core of the lock is inserted, access to the screw 8 is impossible, and therefore, unscrewing of the housing can not be accomplished.

A lock core 10, which contains both a primary and secondary locking mechanism 85 and which has a cross sectional shape, somewhat similar to that of a figure 8, is slidably fitted within a correspondingly shaped opening longitudinally through the housing 1. The primary locking mechanism in this 90 instance, as in the former patent, performs the usual functions of a lock, while the secondary locking mechanism controls the movement of the gate whereby the core is retained within the housing. 95

Secured to the forward end of the core 10, is a circular face plate 11, provided on its inner surface with two parallel ribs 12 and 13, which are dove-tailed within grooves provided in the forward end of the core. 100 This plate is fitted within a recess in the forward end of the housing 1 so that its outer surface lies flush with the collar and thereby presents an attractive appearance, and the plate serves to prevent inward displacement of the core. 105

Rotatably fitted within the lower portion of the core 10, and extending longitudinally therethrough, and also, at its forward end, through the face plate 11, is a key plug 110

14 provided, at its forward end, with an annular shoulder 15 whereby its inward movement is limited and, at its inner end, has secured thereto a throw bar 16. The lower end 5 of this bar is secured, by means of rivets as indicated at 17, to the end of the plug and its edges extend somewhat beyond the peripheral edges of the plug to serve as a means for preventing removal of the plug 10 from the core. The throw portion of the bar is restricted to such length that, when the secondary locking mechanism is actuated, the throw bar will be moved within the limits of the core and will permit its removal 15 through the core opening in the housing. The rivets 17 are formed integrally on the end of the key plug on opposite sides of the key slot.

Fitted to the upper, longitudinal surface 20 of the plug and adapted for limited radial movement with respect thereto within a pocket 19 longitudinally of the key plug opening, is a gate bar 20 provided adjacent its inner end with a laterally extending 25 shoulder 21 (see Figure 6) that is adapted, when the gate is in locking position, to fit within a recess 22 formed at the inner end of the core opening within the housing 1. The lock is provided with pin tumbler locking mechanism; the pins, designated at 24, being contained within tumbler barrels 25 of which there are six in this instance, and which are drilled downwardly from the upper surface of the core through the gate bar 30 and into the key plug, the barrels being formed when the gate is in locking position, as shown in Figure 2. This provides that the pins within the barrels will retain the gate in locked position, except at such times 35 as 40 when a key is inserted for the actuation of the secondary locking mechanism, as will presently be described.

I also provide ejector holes 25' through the lower portion of the core and key plug, 45 in alignment with the barrels 25 through which an instrument may be projected to facilitate the ejection of the pins from the barrels when it is desired that they be removed.

50 Each of the locking pins has two or more breaks which, in the different pins, would be at different positions, and at their lower ends, the pins rest upon balls 26. A key-hole 27 through the plug cuts through the 55 lower ends of the barrels so that, when a key as designated at 28, is inserted it will actuate the pins through contact with the balls. Coiled springs 29 are located in the upper ends of the barrels to bear downwardly against the pins so that they will 60 always be retained in functional position.

It will be mentioned here that, in this construction, the throw bar 16 is provided with an opening 27' for receiving the end of the 65 key and the keys are shouldered as at 28'

to engage the bar which thereby serves as a stop to limit the inward movement of the key and to properly position it for the actuation of the locking tumblers.

In the present lock, the shearing line of 70 the primary locking mechanism is the upper surface of the key plug, and the shearing line of the secondary locking mechanism is the upper edge of the gate. When a suitable key is inserted so as to align a break in all 75 of the pins with the upper surface of the key plug, the latter may then be rotated to actuate the door locking mechanism through the movement of the throw bar 16. Likewise, when a suitable key is inserted whereby a 80 break in each pin is aligned with the upper surface of the gate, the latter, since it will then be turned with the plug, will be moved to unseat the gate shoulder from within the recess 22, and will thereby permit removal 85 of the core from the housing by pulling outwardly on the key.

Upon withdrawing the core, the sections 90 of the several barrels may be re-aligned after moving the gate to locking position, and then the pins may be removed if this is desired for the purpose of changing the combination of the device, or for the purpose of disassembling the parts of the lock.

95 There is a sleeve 30 fitted about, and extending the length of the plug 16 (see Figure 2) which has a longitudinal opening along its upper side. The edges of this opening are seated within shoulders formed along opposite side edges of the gate bar. 100 This sleeve serves as a means for preventing the smaller tumblers from possible displacement from those portions of the barrels within the plug and becoming lodged within the gate opening at the side of the gate; it is apparent that this might be possible, without such a sleeve, if the plug was rotated approximately 15 degrees to the left as 105 shown in Figure 2.

110 In a lock of the character described, it is apparent that by selecting tumblers whereby the breaks of the pins may be varied with respect to their distance from the lower ends of the pins, a great number of different 115 combinations for the primary locking mechanism may be obtained without changing the combination for the secondary locking mechanism. Likewise, by varying the upper tumblers of each pin, so as to change the distance of the upper breaks from the upper 120 ends of the pins, a great many different combinations may be obtained for the secondary locking mechanism.

125 It is readily apparent that the present lock retains all the advantages afforded by the previous lock mentioned, in a simplified, more easily made and assembled construction, and at a smaller cost.

130 It is further apparent that the lock screw positively will prevent removal of the lock.

housing from a door so long as the core is in place, and this core cannot be removed except by authorized persons who possess the key therefor.

5. Having thus described my invention, what I claim as new therein and desire to secure by Letters-Patent, is:

1. In a pin tumbler lock, a lock core having a key plug recess and having aligned 10 transverse perforations at opposite sides of said recess affording unobstructed passageways through said lock core for pin ejecting tools.

2. In a pin tumbler lock, a lock core having a key plug recess extending lengthwise thereof and a key plug operable in said recess, said key plug having transverse perforations and said lock core having diametrically opposite, transverse perforations arranged to align with the perforations in said key plug to afford unobstructed passageways through said lock core for pin ejecting tools.

3. In a lock of the class described, a housing, a core removable from the housing, a key plug having a throw bar fixed thereto, rotatably fixed within the core, a gate bar disposed within the core adjacent the plug and having a shoulder thereon engageable 30 with the housing to normally prevent removal of the core therefrom, a series of pin tumblers extending within the core, through the gate bar, and into the plug; said pins having breaks adapted, by the insertion of suitable keys within the plug, to be aligned 35 with the shear line between the plug and the gate bar to permit rotation of the plug without effecting movement of the gate, or to be aligned with the shear line between the gate 40 and the core to permit movement of the gate with the plug to effect its release from the housing and permit removal of the core.

4. In a pin tumbler lock mechanism, a housing, a core releasably locked within the housing, a key plug rotatable within the core; said core and plug having registering pin tumbler receiving barrels opening at one side of the core and having ejector holes opening from the other side of the core for receiving a pin ejecting tool.

5. In a pin tumbler locking mechanism, a housing having a forward end recess, a core releasably locked within the housing and containing a pin tumbler locking mechanism, a face plate fitted within said housing recess and having a dovetailed connection with the forward end of the core, a key plug rotatable in the core having a shoudered forward end preventing inward movement and a key stop fixed to its inner end overlapping the core to prevent outward movement and having a part normally overlapping the housing as a prevention against removal of the core.

6. In lock mechanism of the class described

a key plug having a key slot extending therethrough and two integral rivets formed on the end of said key plug on opposite sides of said key slot.

7. In lock mechanism of the class described 70 a key plug having a key slot extending therethrough, two integral rivets formed on the end of said key plug on opposite sides of said key slot and a throw member secured to said key plug by said rivets.

8. In combination, a lock casing having a threaded opening and a notch adjacent the opening, a lock housing threaded at one end into the opening and a locking screw 80 threaded from within the housing with its outer end extending therefrom into the notch, for the purpose set forth.

9. In combination, a lock casing having a threaded opening and a notch opening thereinto, a lock housing having an opening therein for receiving a core and having a screw hole leading from said opening to the exterior threaded surface of the housing, and a lock screw threaded into said hole to extend from the housing into said 90 notch, and a core fixed within the housing to normally prevent access to the screw.

10. In a lock of the class described, a housing having an opening therein for receiving a core, and having a recess at its 95 outer end, a core mounted within the opening, a face plate having dove-tailed connection with the outer end of the core and seated within said recess, and locking mechanism within the core engageable with the 100 housing to prevent outward movement of the core, or removal of the face plate.

11. In a locking mechanism, a housing, a core removable from the housing, a key 105 plug rotatable in the core and a key controlled gate for normally locking the core within the housing comprising a sleeve rotatably fitted about the plug and a bar disposed longitudinally of the plug and fitted thereto and having a shoulder adapted to 110 lockingly engage the housing.

12. In a lock of the class described, a housing, a core removable from the housing, a key plug, rotatably within the core having a throw bar fixed thereto, a gate 115 comprising a sleeve that is fitted rotatably to the plug and having a longitudinal opening along one side and a gate bar fitted to the plug within said sleeve opening; said bar having a shoulder thereon engageable 120 with the housing to normally prevent removal of the core therefrom, and key controlled means normally retaining the gate against movement and the plug against rotation, and operable to effect release of the plug for rotation, or to release the gate for movement to disengage the housing.

13. In a lock of the class described, a housing, a core removable from the housing and having a key plug opening, therein, 125

a pocket along one side of the opening for receiving a locking gate, a key plug fitted within the core opening, having a throw bar fixed thereto, a gate bar disposed within the pocket and movable rotatably on the plug and having a shoulder thereon engageable with the housing to normally prevent removal of the core therefrom, key actuated tumbler mechanism mounted within the core and extending through the gate bar and into the plug for normally retaining the gate against movement and the plug against rotation, and operable, by the insertion of different keys within the plug, to

effect the release of the plug for rotation without releasing the gate and for effecting release of the gate for movement with the plug to disengage the gate from the housing and permit removal of the core, and a sleeve fitted about the key plug and having a longitudinal opening, the edges of which are fitted against opposite longitudinal edges of the gate, whereby displacement of the tumblers from the plug within the pocket will be prevented.

Signed at Seattle, Washington, this 11th day of March, 1922.

FRANK ELLISON BEST.
